(57) **CLAIM**

The ornamental design for a display fixture, as shown and
described.

DESCRIPTION

FIG. 1 is a top and front perspective view of a display fixture
showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a top and front perspective view of the display
fixture of FIG. 1 shown with unclaimed environmental
subject matter;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

In the drawings, the broken lines depict unclaimed subject
matter only and form no part of the claimed design.

Applicant reserves the right to amend the claimed invention
by showing in solid lines any and all features or portions
thereof originally shown in broken lines and/or by showing
in broken lines any and all features or portions thereof
originally shown in solid lines.

1 Claim, 12 Drawing Sheets
